UNITED STATES PATENT OFFICE.

JOHN HENRY SIERT, OF BENSON, NEBRASKA, ASSIGNOR OF ONE-FIFTH TO ALVIN H. SIERT, OF BENSON, NEBRASKA, AND ONE-FIFTH TO HILDING L. JACOBSON, OF OMAHA, NEBRASKA.

LAUNDRYING-MACHINE.

1,220,697.

Specification of Letters Patent. Patented Mar. 27, 1917.

Application filed July 17, 1916. Serial No. 109,743.

To all whom it may concern:

Be it known that I, JOHN HENRY SIERT, a citizen of the United States, residing at Benson, in the county of Douglas and State 5 of Nebraska, have invented certain new and useful Improvements in Laundrying-Machines, of which the following is a specification.

This invention relates to an improved 10 laundrying machine, and has for its object, broadly, to provide a machine for washing, rinsing and wringing clothes, which will be convenient in use and may be conveniently and economically manufactured, the mechanism and parts to be so arranged that they 15 will occupy, comparatively, a limited space. The invention consists of the novel construction, combination and arrangement of parts as described herein and claimed, and as 20 illustrated in the accompanying drawing, wherein,—

Figure 1 is a partly broken view of the machine in side elevation. Fig. 2 is a plan view of the same. Fig. 3 is a broken away 25 view on an enlarged scale, showing the dasher and vertical dasher shaft and its bearings, the caps for covering the bushings being omitted. Fig. 4 is a detail relating to Fig. 3, being a plan view of the ratchet 30 wheel for the dasher shaft, the ends of the trackway for the roller of the crank being in section. Fig. 5 is a broken away detail, being a plan view showing the arrangement 35 of pinions at or near the upper end of the vertical driving shaft. Fig. 6 is a bottom plan view of the dasher. Fig. 7 is an enlarged detail, being a section on line 7-7 of Fig. 1, showing a clutch-controlling device for the shaft of the wringer and means to 40 prevent swinging movements of one of the cranes. Fig. 8 is a detail in section, showing a suction cap for the dasher, the section being transversely of and through the middle of the dasher. Fig. 9 is a side view of 45 the parts shown in Fig. 5 to clearly illustrate a clutch employed.

In the drawing, numeral 10 indicates a base or bench, provided below its top with a horizontal, substantially rectangular shelf 50 11, and, disposed centrally of and extending vertically above the base and mounted upon member 11 is a tubular standard 12, its lower end being formed as a spider 13 for sustaining stresses directed transversely of 55 the standard and for housing the gear wheel

14 of the vertical, hollow driving shaft 15 which is disposed within the tubular standard 12, said shaft being adapted to be rotated by any suitable means, as the worm 16 in engagement with the gear wheel 14 and 60 actuated by a motor 17.

Disposed above the base, and mounted to have a horizontal swinging movement on the standard, is a hinge member 17, its wing *a* being provided with arms 18 and 19, said 65 arms, near their ends, as best shown in Fig. 3, being provided with cylindrical bushings 20 in which the vertically disposed dasher shaft 21 may play, this shaft being angular in cross-section, and the bushings (Fig. 1.) 70 having bearings in caps *c* which are mounted on the arms 18 and 19 to permit the required rotatable movements of said shaft and bushings.

Means are provided for causing longitudinal reciprocation and intermittent rotary movements for the dasher shaft, consisting, in part of a horizontal crank shaft 22 in suitable bearings and carried by the wing *a*, its respective ends being provided with 80 a crank 23 and a miter gear 24. The vertical driving shaft 15 is provided near its upper end with a pinion 25. At 27 is indicated a vertical stub shaft having suitable 85 bearings in and carried by the wing *a*, its lower end being provided with a miter gear 28 in engagement with the miter gear 24 of shaft 22, its upper end being provided with a pinion 29 in constant engagement with the 90 pinion 25.

A coupling member is provided for the dasher shaft 21, consisting of a horizontal loop or double trackway 30 provided with outwardly projecting arms or supporting plates 31 circumscribing the circular bushings *b* with which said arms or plates are provided. A ratchet wheel 32' is mounted on the shaft 21 and is disposed between members 31. The end of crank 23 is provided with a tubular pivot-pin 32 (Fig. 4.) 100 upon which is mounted a roller 33 having one of its ends provided with an annular flange, and within said tubular pivot-pin is disposed a pawl or plunger 34 which, normally, projects outwardly of the roller by 105 means of a spring 35.

As thus described, power being provided by the electric motor for rotating the worm, the wheel 14 and shaft 15 will be rotated for causing a corresponding movement of the 110

wheel 25. Shaft 27, obviously, will be rotated on account of its pinion 29 being in engagement with said wheel 25, and on account of the engagement of the miter gear 24 with the miter gear 28, the shaft 22 will be rotated, its crank 23 causing the roller 33 to reciprocate horizontally in the loop or double trackway 30, each rotation of the shaft 22 causing a downward and an upward movement of the dasher shaft, the strokes of said shaft depending upon the length of the crank arm 23; and by referring to Fig. 4 it will be seen that when the roller moves in one direction, the pawl 34 will engage a tooth of the ratchet wheel 32 to cause the intermittent movement of the dasher shaft.

In operation, since the rotary movement of the dasher shaft will occur while it is disposed between its uppermost and lowermost positions, the dasher may be free from the contents of the tub during said movement, which of course is a desirable feature.

25 The mechanism thus described is of great advantage for washing clothing or other fabrics in conjunction with a dasher 37 which is mounted on the lower end of shaft 21 since the dasher may move downwardly upon the fabric within the tub α with a desired impacted force and also will be swung horizontally a limited distance before each downward movement, to thereby engage different parts of the clothing or fabrics, at each stroke.

40 The dasher 37 is of elliptical form, in plan, as best shown in Figs. 6 and 8, and consists of a casing 38 provided, on its inner side, with circular compartments 39, each having a cone-shaped top so that water which enters therein or the greater part thereof will be confined, approximately, near its open, lower end, cross-partitions 40 being provided for each compartment, and suitable apertures 41 also provided so that, during operation, water or air may pass therethrough.

45 As described, it may be stated that the vertical, tubular standard 12 operates as a pintle for the hinge member 17, and upon this standard is also mounted, to swing horizontally, a second hinge member 42, its wing c having a horizontal extension 43, preferably of angular form in cross-section, to provide a horizontal flange d upon which may be mounted a clothes wringer 44.

50 Mechanism is provided so that, during operation, clothing or other fabrics may enter from either side of the wringer to pass between the rollers thereof, this often being a matter of convenience since a plurality of tubs are employed, either for containing rinsing water or for use in connection with the wringer and dasher. Also 55 means are provided so that the wringer and

dasher shaft may be operated coincidently or separately. The lower roller e of the wringer is provided with a shaft 45 having two miter gears 46 and 47 mounted thereon as idlers, near its inner end. At 48 (Figs. 70 1. 7.) is indicated a clutch which is feathered on shaft 45, and by means of a hand lever 49 the clutch may be moved on said shaft into engagement with either of the gears 46 or 47. At 50 is indicated a shaft having 75 bearings in the upper part of the wing c , its upper end being provided with a pinion 51 constantly in engagement with pinion 26, its lower end being provided with a miter gear 52 in constant engagement with the 80 miter gears 46 and 47. It will be understood that when a rotation in one direction of the roller e of the wringer is desired, the clutch may be moved into engagement with the gear 46, and that the roller may be 85 rotated in an opposite direction by moving the clutch into engagement with the gear 47, and the roller e will not be rotated if the clutch is not engaged by either of these gears.

90 The pinion 26 is provided with a clutch 69, best shown in Fig. 9, and is also provided with a pull-rod 70 (Figs. 1. 7. 9.) which is disposed within the hollow shaft 15. The pinion 25 is provided with a recess 71, indicated by broken lines in Fig. 9, the walls of said recess being of such form that, when engaged by the clutch 69, the rotatable movement of the driving shaft 12 and its pinion 25 will be imparted to said pinion 26.

95 Since the tubs α , γ and β should be suitably supported and maintained in such positions adjacent to each other as will be convenient for the work of an operator, and since the dasher shaft and wringer should be disposed above and in line with the center of the tubs, the base 10 is provided with radially disposed collapsible frames or supports 53, these being disposed substantially 100 90 degrees apart. Each frame 53 consists, 105 as best shown in Fig. 2, of a plate 54 provided at its side edges with opposed wings 55 and a narrow shelf or arm 56 hingeably connected at 57 to the inner end of the plate 54, the outer end of the plate having 110 a hingeable connection, as indicated at 58 with the base 11, the free end of the shelf 56 being provided with a lug or toe-piece 58', each wing also being provided with a lug 59. The shelves 56 may be swung inwardly of the base, when not in use, the lugs 58' engaging in notches or depressions 60 (Fig. 1.) of the base, and when the tubs are 115 disposed on the frames 53, the lugs 58' and 59 will engage their sides near their bottoms 120 as means for holding them upon the frames, and it will be understood that, by applying a suitable force, the tubs or any one of them, while disposed on said frames, may 125 be tilted or swung outwardly and partly 130

overturned, this being a matter of great convenience when removing their contents.

As best shown in Fig. 7, the tubular standard 12 is provided with recesses 61 opening on its side, these being disposed 90 degrees apart. The wing *a* is provided with a pin or keeper 62 which is normally pressed toward the standard by means of a spring 63, the movement of the pin being 10 under control of a hand lever 64, and it will be understood that the hinge member 17 and mechanism carried thereby may be shifted or swung horizontally so that the dasher will be disposed above any of the 15 tubs, the pin 62 entering one of the recesses 61, to maintain the parts stationary.

Also similar means are provided for a control of the hinge member 42 when its wing *c* has been shifted or swung horizontally. At 65 is indicated a rod having bearings in the extension 43 of the wing *c*. It is normally pressed toward the tubular standard 12 by the spring 66 and is under control of the hand lever 67 for an outward 25 movement, recesses 68, similar to recesses 61 being formed, substantially 90 degrees from each other to open on the side of the standard, in any one of which the rod 65 may engage so that the wringer may be held in 30 a stationary position above any one of the tubs.

Since the wringer is used only for limited periods of time compared with the time required for washing, it is desirable that it be under full, immediate, and convenient control of an operator, and therefore a treadle member is provided for causing operation, or for terminating the movement of the wringer. The pull rod 70 is normally 40 pressed upwardly by a spring 72 which is mounted on the bottom of shelf 11 so that the clutch 69 will, normally, be disengaged from the pinion 25, and a downward movement of this rod may be caused by the lever or 45 treadle-arm 73 which is pivotally mounted between its ends at 74 upon the lower end of the rod, for use in moving this clutch into engagement with said pinion 25. One of the ends of the lever 73 is provided with 50 a roller 75 adapted to bear on the lower side of the shelf 11, its opposite end being provided with a foot-piece 76, and it will be understood that the lever 73 may be swung horizontally so that the foot-piece will be 55 disposed near any one of the tubs so that an operator, by pressing downwardly upon the foot-piece, may cause operation of the wringer, and upon removing said pressure, operation of the wringer will be terminated.

60 In order that the dasher shaft and washing mechanism will not be in operation at

times when it is desired to use the machine for wringing, the shaft 27 is provided (Fig. 1.) with a clutch 77, normally in engagement with the miter gear 28 by means of the 65 spring 78, said clutch being under control of the hand-lever 79.

Having described construction, a further explanation relating to operation is not necessary.

What I claim and desire to secure by Letters Patent is—

1. In devices for the purpose described, a tubular standard, a hinge member mounted thereon, a vertical shaft journaled in the 75 hinge member and provided with a dasher, a crank shaft journaled in the hinge member, a rotatable shaft circumscribed by the tubular standard, and a plurality of co-acting gear wheels for communicating the 80 movements of the rotatable shaft to the crank shaft for causing longitudinal reciprocation of the vertical shaft.

2. Devices for the purpose described, comprising, in combination with a base, a tubular standard projecting above the base, a hinge member mounted to swing horizontally on the standard, a vertical shaft journaled in the hinge member and provided with a dasher, a crank shaft journaled in 85 the hinge member, a rotatable shaft circumscribed by the tubular standard, a plurality of co-acting gear wheels for communicating the movements of the rotatable shaft to the crank shaft for causing longitudinal 90 reciprocation of the vertical shaft, and means for preventing relative movements of the hinge member and standard after said hinge member has been swung horizontally.

3. In devices for the purpose described, a 100 tubular standard, a hinge member mounted thereon, a vertical dasher-shaft having bearings in the hinge member, a crank shaft journaled in the hinge member, a rotatable driving shaft provided with a pinion and circumscribed by the tubular standard, co-operating mechanism on the vertical dasher-shaft and hinge member for communicating the movements of the pinion of the driving shaft to the crank shaft to cause longitudinal 105 reciprocation of the dasher-shaft, and mechanism on the vertical dasher-shaft and crank shaft arranged for co-operation to impart an intermittent rotary movement to said dasher-shaft during the longitudinal 110 reciprocation thereof.

In testimony whereof, I have affixed my signature in presence of two witnesses.

JOHN HENRY SIERT.
